UNITED STATES PATENT OFFICE.

LOUIS ROSENBERG, OF NEW YORK, N. Y.

COVERED BUTTON.

Application filed July 9, 1921. Serial No. 423,459.

To all whom it may concern:

Be it known that I, LOUIS ROSENBERG, a citizen of the United States, and a resident of the city of New York, State of New York, have invented certain new and useful Improvements in Covered Buttons, of which the following is a specification.

This invention relates to buttons and similar articles and more particularly, to a covered button such as is commonly used upon garments when it is desired to eliminate the contrast between the material of the button and the material of the garment.

Such covered buttons as are common in the art have heretofore been sewn or attached to the garment by hand, a time consuming and laborious operation. In such constructions the material is gathered in a tuft at the center of the rear side of the button so as to provide holding means for the thread. As is well known, this means of attachment for the button is more or less insecure so that the button frequently becomes detached and lost.

It is the primary purpose and object of the present invention to provide a covered button which can be readily attached to the material of the garment by machine. In the accompanying drawing I have disclosed several embodiments of the invention each of which is characterized by the provision of a two part metallic body, each of the parts having a marginal flange and being so constructed that the edge of the covering material is securely gripped or clamped between the flanges, the said material extending over the front side of the button body and one of the parts of the metallic body having a plurality of spaced needle guide openings which are entirely concealed from view by the covering material.

In one of the suggested constructions of the invention I propose to use a disc of cardboard or other similar material interposed between the two parts of the button body and likewise having spaced openings aligned with the needle guide openings but of smaller diameter than the latter so as to hold the thread strands away from the edges of the openings in the metal part and thus obviate the possible cutting of the same.

With the above and other objects in view, the invention consists in the improved button construction and in the form, proportion and arrangement of its several detail

parts as will be hereinafter more fully described, illustrated in the accompanying drawing and subsequently incorporated in the subjoined claims.

In the drawing wherein I have disclosed several desirable and practical embodiments of the invention and in which similar reference characters designate corresponding parts throughout the several views:

Figure 1 is a diametrical sectional view through a covered button showing one construction of my invention;

Figure 2 is a front elevation, a part of the covering material being broken away;

Figure 3 is a rear elevation;

Figure 4 is an enlarged fragmentary perspective view;

Figures 5, 6, 7, and 8 are views respectively corresponding to Figures 1 to 4 and illustrating a slightly modified form of the invention;

Figure 9 is an enlarged fragmentary elevation illustrating the manner in which the threads are held out of contact with the edges of the needle guide openings; and

Figures 10, 11, 12 and 13 are views corresponding to Figures 1 to 4 and showing still another embodiment of the invention.

Referring in detail to the drawings and more particularly to Figures 1 to 4 thereof, 5 designates the front section of the button body and 6 the rear section thereof. Each of these body sections is constructed from a single sheet metal plate, the section 6 being in the form of an annulus having an opening 7 of relatively large diameter. Each of these metallic sections of the button body is provided upon its edge with an annular marginal flange 8 and 9 respectively, said flanges extending at right angles to the plane of the metal plate from which the body section is formed.

The front section 5 of the button body is further provided with a plurality of needle guide openings 10 equi-distantly spaced from each other and concentrically located with respect to the axial center line of the button. These needle guide openings are so spaced and grouped that they are all disposed within the area of the opening 7.

The fabric covering material shown at 11 is adapted to be tightly drawn over the front surface of the button section 5 and the edge thereof turned inwardly around the flange 8 of said body section. The marginal flange 9 of the other metal body

section 6 of the button is then inserted within the flange 8 as clearly shown in Figure 1 so that the edge of the material is tightly compressed or clamped between 5 said flanges. The relative diameter of the flanges 8 and 9 is such that considerable pressure must be applied to the button section 6 in order to assemble the same with the section 5 whereby its flange 9 is placed 10 under tension. There is thus a constant clamping and holding pressure of the flanges 8 and 9 upon the edge of the material so that it cannot become loosened or detached from the body of the button.

15 In the sewing of a button constructed in the manner described, upon the garment, the button is positioned in the sewing machine in the same manner as the ordinary button of bone or composition material having 20 needle guide openings. The needle first penetrates through the material 11 and passes through one of the guide openings 10, then through the opening 7 and through the material of the garment. After 25 several thread loops have been drawn through one of the openings, the needle then carries the thread across the face of the covering material 11 and is reciprocated through another of the openings 10 in the usual manner. Thus the button may be 30 very tightly sewn to the garment and as the guide openings 10 for the needle are entirely covered by the material 11, they will not be visible, and only the securing thread 35 will be seen upon the surface of the material. By the provision of a covered button of this construction which can be rapidly secured upon the garment by machine, considerable economy may be realized 40 in the manufacturing cost of such garments.

In Figures 5 to 9 inclusive, I have shown another slightly modified construction in which the parts of the button body are of 45 identically the same construction as those above referred to, but in addition, I provide a disc 12 of cardboard or other suitable material which is interposed between the spaced plates from which these button sections are formed. The inner edge of 50 the annular metallic section 6 of the button engages tightly against the rear side of this disc so that it is closely confined between the sections of the button. The disc 55 12 is provided with spaced openings 13 which are grouped in the same manner as the openings 10 in the front section 5 of the button and are in registering relation with the latter openings. It is to be noted, 60 however, that the openings 13 in the disc 12 are of a less diameter than the openings 10, such construction being clearly disclosed in Figures 6, 8 and 9.

In the latter figure, it will be noted that 65 the attaching threads T are compactly held

within the openings 13 of the disc and away from the edges of the openings 10 in the metal button section 5. Thus it is apparent that in the lateral pull or strain upon the button, the threads will not come in contact with the edges of the openings 13 which would probably result in the cutting or severance of the threads.

70 In Figures 10 to 13 of the drawings, I have disclosed another construction where- 75 in the front section 5' of the button body is in the form of a metal annulus while the rear section 6' is of disc form. The metal body sections, however, are provided with the marginal flanges as above referred 80 to for securely clamping and holding the edge of the covering material which ex- 85 tends over the annulus 5'. In this case the rear metal section 6' of the button is pro- 90 vided with the spaced needle guide open- 95 ings 10'. As no support is provided for the central portion of the covering material, the attaching threads will draw the mate- 95 rial in slightly towards the rear section 6' of the button, and for this reason, this form 100 of the invention may not be so desirable. It will be manifest, however, that if de- 105 sired, the disc 12 may also be used in connection with this construction and confined 110 within the marginal flange of the button section 6'.

From the foregoing description con- 105 sidered in connection with the accompa- 110 ny drawing, the construction and several 115 advantages of the various illustrated em- 120 bodiments of the invention will be readily understood. The covered button of my invention can be constructed in various sizes and of different ornamental shapes as 125 might be required and by attaching the same to the garment by machine in the same manner as the ordinary uncovered button, maximum security and at the same time, neatness in appearance with economy in 130 production is obtained.

135 While I have above referred to several practical embodiments of the device, it will nevertheless be understood that the invention might also be embodied in various other alternative forms, and I accordingly 140 reserve the privilege of resorting to all such legitimate changes in the form, proportion and relative arrangement of the several parts as may be fairly embodied within the 145 spirit and scope of the invention as claimed.

I claim:

1. A button of the character described comprising a body section, a second body section co-acting therewith covering mate- 150 rial adapted to be extended over the side of the first-mentioned body section opposite from the second body section, said sections having means for clamping the covering mate- 155 rial in position on the first-mentioned section, and said first-mentioned section being 160

provided with spaced needle guide openings concealed by the covering material.

2. A button of the character described comprising two body sections having annular marginal flanges, a sheet of covering material extending over the side of one of said body sections, the edge of said material extending between said flanges and being clampingly held thereby, and said body section over which the covering extends having a plurality of spaced needle guide openings therein concealed by said material.

3. A button of the character described comprising two sheet metal body sections each having an annular clamping flange, a sheet of covering material extending over one side of one of said body sections and having its edge clampingly held by said flanges, the other of the body sections being provided with an aperture and said first named section having a plurality of spaced needle guide openings therein, concealed by the covering material and grouped within the area of said aperture.

4. A button of the character described comprising a body section provided with spaced needle guide openings, covering material adapted to be extended over one side of said body section so as to conceal said openings, and means co-acting with said body section on the side opposite from the covering material to secure the covering material in place on said body section.

5. A button of the character described

comprising a body section having a transversely extending flange and provided with spaced needle guide openings arranged concentrically in the central portion of the section, covering material adapted to be extended over one side of said section and over the outer and inner sides of said flange, and a second section co-acting with said flange to clamp the covering material in place on the first-mentioned section, said second section being formed with a central aperture of greater diameter than the circle defined by the needle guide openings so as to permit a needle to pass entirely through the button at any of said openings.

6. A button of the character described comprised of two sections and a sheet of covering material, one of said sections constituting a backing for the covering material and being formed with needle guide openings concealed by the covering material and the other section being operable to clamp the covering material on the first-mentioned section.

7. A button of the character described comprising a bottom section, a top section formed with needle guide openings, and a sheet of covering material extending over the top section and concealing said openings.

In testimony that I claim the foregoing as my invention, I have signed my name hereunder.

LOUIS ROSENBERG.
